UNITED STATES PATENT OFFICE.

JAMES CHARLES FLIGHT, OF SWAN HILL, VICTORIA, AUSTRALIA.

PLATFORM ADJUSTMENT.

1,135,572.

Specification of Letters Patent. Patented Apr. 13, 1915.

Application filed August 20, 1913. Serial No. 785,766.

To all whom it may concern:

Be it known that I, JAMES CHARLES FLIGHT, of Swan Hill, in the State of Victoria, Commonwealth of Australia, farmer, have invented certain new and useful Improvements in or Attachable to Platform Adjustments, of which the following is a specification.

This invention relates to improvements in strippers, stripper-harvesters and like machines and has been devised for the purpose of providing exceedingly simple and efficient means for raising and lowering the combs to accommodate grain crops of varying heights.

Now the present invention provides a simple and strong mechanism which is actuated by chain and sprocket gearing from the main wheel and is easily controlled by a slight movement of a lever located adjacent to the driver's seat.

In order that the invention may be more readily understood reference will now be had to the accompanying sheet of explanatory drawings, wherein—

Figure 1 is a view in plan of the improvements comprised in the present invention and shows their adaptation to part of an existing type of stripper which is indicated by dotted lines. Fig. 2 is a view in side elevation of Fig. 1. Fig. 3 is a detail view showing part of the control lever and part of the automatic means for throwing the lever to the off position. Fig. 4 is a detail view showing part of the operating lever and also showing the same fitted with an attachment for preventing the accidental operation of the comb.

In these drawings like characters of reference have been employed to indicate similar parts in the different views and the numeral 1 designates a curved rack the teeth of which engage with a pinion 2 fitted to a short spindle 3 mounted transversely in bearings 4 fitted to the top of the main frame 5 of the machine. The said spindle 3 also carries a pinion or worm wheel 6 which gears with a worm 7 on a longitudinally disposed shaft 8 mounted revolvably in bearings 9 fitted to the frame. The said shaft 8 is located at one side of the rack 1 and its rear end is fitted with a bevel gear 10 having bevel teeth adapted to engage oppositely disposed bevel pinions 11 carried on a transverse shaft 12. The forward bearing 9 preferably comprises a center screw 13 which can

be adjusted to any degree of nicety in a bracket 14 and retained in a desired position by a jamb nut 15. The inner end of said shaft 12 carrying the bevel pinions 11 is fitted with a sprocket wheel 16 which is connected by a chain 17 to a sprocket 18 fitted to the hub 19 of the main wheel 20.

Any approved form of tension or adjustment device can be employed to regulate or take up the slack of, or free the chain 17.

The bevel pinions 11 normally are arranged to run free on the shaft 12 and are adapted to impart motion to the bevel gear 10 in different directions when engaged by a clutch 21 slidably mounted on the said shaft. The said clutch 21 may slide on a feather key (not shown) and its ends are formed with jaws 22 corresponding with teeth 23 on the inner faces of the pinions. The said clutch 21 is moved from side to side to engage either of the said pinions by an arm 24 fitted to the rear end of a shaft 25 disposed longitudinally beneath the frame and mounted in bearings 26. The lower end of an operating lever 27 is fitted rigidly to the shaft 25 and projects upwardly through the frame 5 in advance of the face wheel. The said lever 27 may be slotted at 28 (see Fig. 3) to accommodate the longitudinally disposed shaft 8 and it can be retained in its central or other position by a quadrant 29 fitted to the top of the main frame. The shaft 25 is provided with a laterally projecting arm 30 having at its end a jaw 31 which is adapted to engage loosely a curved rod 32 fitted to the movable frame 33 of the machine and to the upper end of the said rack 1.

The curved rod 32 is fitted at approved positions with adjustable stops 34 which are arranged to press the arm 30 downwardly or upwardly when the comb 35 is nearing its lowest or highest elevation.

The downward or upward movement of the said arm 30 causes the lever 27 to be swung over to the central position thereby throwing the mechanism out of gear automatically and preventing injury or breakage of the parts thereof.

If preferred the operating lever 27 can be fitted with an additional device to prevent the accidental operation of the comb due to gravity or the jar incident to travel such as a hand lever 36 and spring actuated pawl 37 adapted to engage a ratchet wheel 38 fitted to the shaft 8. When the lever 27

is held by the quadrant 29 and the pawl 37 is engaged by the ratchet wheel 38 the longitudinally disposed shaft 8 is held rigidly in position against rotation and consequently the pinion 2 meshing with the curved rack 1 cannot move until the pawl 37 is released and the lever operated thereby preventing any accidental movement of the comb. Owing to the arrangement of the parts, the pawl 37 will mesh with the ratchet wheel 38 only when the lever 37 is engaged by the quadrant 29.

It will be readily understood from the foregoing description that the comb can be quickly raised and lowered by moving the operating lever 27 to and from the driver and that the force required will be very slight and furthermore, that efficient provision is made for preventing the mechanism raising or lowering the comb beyond the limit of the rack.

While I have described in the foregoing specification the construction of parts and operations preferred, I am aware that numerous changes of construction and operation may be made without departing from the spirit and scope of the invention, and I, therefore, do not wish to be understood as limiting myself by the positive terms employed in connection with the description, excepting such as the state of the art may require.

What I do claim is:—

1. In a raising and lowering device for the combs of agricultural machines combination with a curved rack fitted to a movable part of the machine, of a pinion fitted to a transverse spindle, a worm wheel on said spindle meshing with a worm on a longitudinal shaft, a gear wheel on the end of said longitudinal shaft, bevel pinions en-

gaging said gear wheel and mounted on a transverse shaft, a double clutch to engage said pinions, a lever for operating said clutch, gearing for transmitting motion from the main wheel or axle to the said shaft, and means for throwing said clutch out of gear automatically when the curved rack has reached the limit of its travel, said means comprising an arm rigidly connected to the operating lever, a jaw on the outer end of said arm, a rod fitted to the movable part of the machine frame and engaged by said jaw, and stops on said rod for engaging said jaw, substantially as described.

2. In a raising and lowering device for the comb of agricultural machines combination with a curved rack fitted to a movable part of the machine, of a pinion fitted to a transverse spindle, a worm wheel on said spindle meshing with a worm on a longitudinal shaft, a gear wheel on the end of said longitudinal shaft, bevel pinions engaging said gear wheel and mounted on a transverse shaft, a double clutch to engage said pinions, a lever for operating said clutch, gearing for transmitting motion from the main wheel or axle to the said shaft, an arm fitted to the operating lever or shaft carrying the same, a jaw or the like on the outer end of said arm, a rod fitted to the movable part of the machine frame and engaged by said jaw, and stops on said rods, substantially as described and for the purposes set forth.

In witness whereof I have signed this specification in the presence of two witnesses.

JAMES CHARLES FLIGHT.
